[57] CLAIM

The ornamental design for an index card box, as shown and described.

DESCRIPTION

FIG. 1 is a side elevational view of an index card box showing my new design, the opposite side being a mirror image thereof;

FIG. 2 is a right end elevational view thereof;

FIG. 3 is a left end elevational view thereof;

FIG. 4 is a bottom plan view thereof;

FIG. 5 is a top plan view thereof;

FIG. 6 is a modified form of the index card box wherein the only difference is the reverse positions of the compartment separators; and

FIG. 7 is a further modification of the index card box wherein the only difference is the vertical positions of the compartment separators;

FIG. 8 is a bottom plan view of FIG. 6; and

FIG. 9 is a bottom plan view of FIG. 7.
